UNITED STATES PATENT OFFICE.

ANTONY GABRIEL, OF CINCINNATI, OHIO, AND JOSEPH STUBBERS, OF COVINGTON, KENTUCKY, ASSIGNORS TO THE INCANDESCENT LIGHT AND STOVE COMPANY, OF CINCINNATI, OHIO, A CORPORATION.

MANTLE-HOLDER FOR GAS-BURNERS.

SPECIFICATION forming part of Letters Patent No. 777,199, dated December 13, 1904.

Application filed June 17, 1904. Serial No. 212,979. (No model.)

To all whom it may concern:

Be it known that we, ANTONY GABRIEL, residing at Cincinnati, in the county of Hamilton and State of Ohio, and JOSEPH STUBBERS, residing at Covington, in the county of Kenton and State of Kentucky, citizens of the United States, have invented certain new and useful Improvements in Mantle-Holders for Gas-Burners, of which the following is a specification.

Our invention relates to an improved mantle-holder for gas-burners.

The features of the invention are more fully set forth in the description of the accompanying drawings, forming a part of this specification, in which—

Figure 1 is a central vertical section of globe-holder, showing mantle-support in elevation. Fig. 2 is a top plan view of the same with globe omitted and showing mantle-stem in section. Fig. 3 is an enlarged section on line $\alpha\alpha$, Fig. 2. Fig. 4 is a section of globe-holder with a modified form of mantle-support. Fig. 5 is a perspective view of the mantle-support.

1 represents the burner-tube.

2 represents the globe (or chimney) supported upon the burner-holder. This holder consists of a sleeve portion 3 fitting over the top of the burner-tube and seating upon the flange 4 thereof. The sleeve 3 has the three arched depending arms 5, on the lower edge of which is formed the annular tray 6 for holding the globe. Attached to the under side of the tray and under one of the arms 5 is a substantially reversed looped spring 7. The lower portion of this spring is provided with an orifice 8 in substantial alinement with the orifice 9 in the arm 5.

10 represents the mantle supported by the yoke 11, the stem 12 of which passes through the orifices 8 and 9. The upper looped portion of the spring 7 is normally substantially

in line with the orifices 8 9, so that the wire 12 has to push the looped end inward in order to engage into both orifices 8 9. The tension of this looped end holds the stem 12 in place. This arrangement is very simple, cheap, and effective, it can readily be used for inserting or removing the wire, and it avoids the use of a screw or other clamp which would strain or bend the wire and which require two hands in manipulating. Moreover, this arrangement holds the wire 12 in true vertical position. The insertion of the wire 12 through the orifices 9 and 8 engages the loop end of the spring and automatically clamps the wire in position in the act of inserting it.

In Fig. 4 we have shown the spring 7 reversed—*i. e.*, with the looped end pressing downwardly projecting against the lower end of stem 12 below the orifices 8 and 9. It is obviously equivalent to the other method.

Having described our invention, we claim—

In combination with a gas-burner, mantle, wire-support, and globe-holder, said globe-holder being provided with an orifice for the insertion of the mantle-supporting wire, a spring attached to the said holder, there being formed in the attached end of the spring, an orifice for the insertion of the mantle-supporting wire disposed in the vertical line of the first-named orifice, the free end of the spring being inwardly looped and interposing a curved surface in the line of the orifices whereby in inserting the wire into the orifices, the spring is engaged and automatically clamps the wire in position.

In testimony whereof we have hereunto set our hands.

ANTONY GABRIEL.
JOSEPH STUBBERS.
